UNITED STATES PATENT OFFICE

LEWIS A. FURLONG, OF NEWBURYPORT, MASSACHUSETTS

DESIGN FOR A TRELLIS

Application filed April 11, 1930. Serial No. 35,213. Term of patent 3½ years.

To all whom it may concern:

Be it known that I, LEWIS A. FURLONG, a citizen of the United States of America, residing at Newburyport, in the county of Essex and State of Massachusetts, have invented a new, original, and ornamental Design for Trellis, of which the following is a specification, reference being had to the accompanying drawing, forming part thereof.

Fig. 2 is a side elevation thereof.

I claim:

The ornamental design for a trellis as shown.

LEWIS A. FURLONG.
